Section 1, Public Law 690, August 8, 1946
Patent expires January 4, 1964

11 Claims. (Cl. 179—171.5)

1

The present invention concerns an arrangement for modulating the anode voltage of the high frequency power stage of a transmitter consisting of a high and low frequency part. With such an arrangement an alteration in the anode voltage also causes the interval of time during which the anode current flows or the anode current "flow angle" to vary. With modulation peaks of the low frequency modulation voltages this angle becomes larger, the efficiency correspondingly lower and the maximum power output too small. The modulation characteristic II shown in Fig. 1 which represents the relationship between the high frequency anode alternating voltage E_w and the anode direct voltage E_a for a constant alternating grid voltage, is thus a curve and not the desired straight line I. Due to the non-linear connection between the values E_w and E_a appreciable distortions are caused with a high degree of modulation. In addition there are also distortions due to a variation in the load resistance of the modulator which is formed by the high frequency power stage.

These disadvantages are avoided according to the invention by the control grid bias voltage of the high frequency power stage and simultaneously the anode voltage of the tube stage in front of the high frequency power stage being subjected in opposite phase and in phase respectively to a modulation with a modulation depth at least about equal to the anode voltage of the high frequency power stage.

The invention possesses several advantages when compared with known arrangements. Since the power of the stage in front of the high frequency power stage is regulated by altering the anode voltage in rhythm with the modulation voltage, this is only subjected to a maximum load during the voltage peaks and not continuously. The mean power required can thus be considerably reduced for this stage so that the life of the tubes in this stage are considerably prolonged. The average efficiency of the end stage becomes greater, because it does not decrease during the voltage peaks but maintains its value; at the same time the distortions become smaller. Furthermore the improved efficiency enables the tubes to be better utilized. Finally it is possible by means of suitable small deviations of the modulation depth of the control grid bias voltage of the high frequency power stage and/or the anode voltage of the tube stage in front of this stage to obtain practically an exact straight line curve for the modulation characteristic from the curve which is identical with that of the modula-

2

tion depth of the anode voltage of the high frequency power stage, thus eliminating distortions.

In the drawings which illustrate constructional examples of the invention, Fig. 1, already referred to, is a plot showing the relationship between anode direct voltage and high frequency alternating voltage with constant alternating grid voltage; Fig. 2 is a schematic diagram of one form of the invention; Fig. 3 is a plot showing the grid voltage-anode current characteristic of a tube; and Fig. 4 is a schematic view of a modified form of the invention. The high frequency carrier oscillations are produced in the high frequency part of the transmitter arrangement shown in the upper portion of Figures 2 and 4. The low frequency amplifier shown below serves to form the modulation voltages.

In Fig. 2 reference numeral 1 indicates an oscillator for producing high frequency (RF) oscillations which reach the grid of tube 2 where they are amplified. In the anode circuit of this tube is an oscillation circuit 3 which acts as a load. If necessary a frequency multiplication can be combined with this amplification.

25 The high frequency alternating voltages are taken from this oscillation circuit 3 and passed over a coupling condenser to the grid of the next stage. The grid circuit of this stage is formed by an inductance 4, a grid bias voltage source 5 and a choke coil 6 which does not allow low frequencies to pass, these elements being connected in series. Tube 7 is connected to an oscillation circuit 8 from whence the power is supplied to an antenna or a further stage.

35 The speech frequencies are amplified in a low frequency amplifier. This consists of the audio or speech frequency (AF) source 11, tubes 12 operating in push-pull connection, and transformer 13. In parallel with the secondary winding of the latter is a choke coil 14. The anode voltage passes to terminal 15. Condenser 16 prevents the direct anode current of tube 7 from flowing through the secondary winding of transformer 13. This current finds a path through choke coil 14.

40 In service a voltage drop, which also appears at choke coil 14, occurs in the secondary winding of transformer 13 in rhythm with the speech frequencies supplied to the amplifier 11. By this means oscillations are obtained in oscillation circuit 8, the amplitude of which varies in rhythm with the low frequency signal, and thus the high frequency oscillations amplified in tube 7 have their amplitude modulated.

45 If now at a certain moment due to the low

frequency amplification, the voltage drop at choke coil 14 becomes smaller and thus the anode voltage of tube 7 greater, the grid voltage and anode current characteristic III in Fig. 3 will be displaced to the left in the direction of the negative grid voltage. This figure shows in a known manner the course of the anode current i_a as a function of the grid voltage e_g , a sinusoidal alternating voltage being shown in the lower part of the figure as a function of the time T . From Fig. 3 it is clear that when the curve III is moved to the left, the grid bias voltage remaining unchanged, the time interval during which the anode current flows (indicated by the angle θ) becomes greater, whilst the time interval during which no anode current flows becomes smaller due to the anode voltage increasing. This is known to decrease the efficiency. This disadvantage can now be avoided, if for instance when doubling the anode voltage of the tube 7 its grid bias voltage is also doubled in a negative sense, whilst at the same time the anode voltage of tube 2 is doubled in phase with the anode voltage of tube 7. Generally the grid bias voltage of tube 7 and the anode voltage of tube 2 have to be modulated in opposite phase and in phase respectively with a modulation depth which is identical with the depth of modulation of this voltage. With the constructional example shown in Fig. 2 the voltage for modulating the anode voltage of tube 2 is obtained at point 17 of choke coil 14 and supplied over oscillation circuit 3 to the anode of this tube. By this means it is possible to maintain the current flow angle θ and therefore the efficiency of tube 7 constant.

By tapping the voltage off at the point 17 the depth of the modulation can be correctly adjusted if the anode voltage of tube 2 differs from that of tube 7. Even if the anode voltages are equal choke coil 14 provides a useful means of adjustment.

A modified form of the invention is illustrated in Fig. 4. Elements corresponding to those already shown in Fig. 2 are indicated by the same reference numerals, so that these elements and their method of operation do not require to be described again. In the modified arrangement shown in Fig. 4 the modulated high frequency stage, which can be an end or intermediate stage, consists of two tubes 7 in push-pull connection. Transformer 21 serves to control the grid and anode voltages. The primary winding 22 of the transformer has an alternating anode current flowing through it because that half of the choke coil 9 which is at the cathode side prevents this current from flowing to earth. This alternating anode voltage produces two voltages in transformer 21, one of which lies across the winding 23; it serves to influence the grid bias voltage of tubes 7. The second voltage which is necessary for controlling the anode voltage of tube 2 is taken from the secondary winding 24. It is fed over condenser 25, which is required to separate the direct anode voltage from the earth potential, and over the inductance of the oscillation circuit 3 to the anode of tube 2. Choke coil 26 prevents the alternating currents from flowing away over the anode voltage source.

An advantage of the arrangement shown in Fig. 4 is that the power required for the additional anode and grid modulation is obtained from the cathode circuit of the high frequency end stage. This power extraction has the character of a feed-back coupling and possesses the advantages inherent to such a connection.

An important feature of these arrangements is that it is immaterial if the magnitude of the voltage variations is not exactly proportional with the modulation depth of the alternating anode voltage of tube 7. Since namely by means of small deviations of the voltage variations from such a proportional curve it is possible to ensure that the modulation characteristic II in Fig. 1 assumes a straight line course corresponding to the characteristic I, a particular advantage of the arrangement according to Fig. 2 or 4 is that the anode voltage modulation is free from distortion and the efficiency also remains constant.

The arrangement in Fig. 2 can be simplified if choke coil 14 is omitted. In this case the anode current of tubes 2 and 7 flows through the secondary side of transformer 13.

In order to be able to obtain the correct phase position for the feed back voltages, it is advisable to conduct these voltages over phase-adjusting elements.

The high power stage formed by tubes 7 can consist of a single tube or several tubes connected in push-pull or in parallel. It is preferably connected in such a manner that it operates as a class C amplifier. The tubes of this stage can also be operated in class B or A, without the advantages resulting from the invention being thereby affected.

I claim:

1. In a transmitter, a high frequency part comprising; an oscillator producing a high frequency carrier wave, an amplifier stage arranged for amplifying the output of said oscillator, and a power stage connected to the output of said amplifier stage; a low frequency part comprising a source of audio frequency modulating potential; means to modulate the amplitude of said carrier wave in accordance with said modulating potential; and means simultaneously subjecting the grid bias potential of said power stage and the anode potential of said amplifier stage in opposite phase and in phase, respectively, to a modulation having a modulation depth at least approximately equal to that of the anode potential of said power stage.

2. A transmitter as defined in claim 1, characterized by the feature that said last means includes a transformer, one winding of which has at least a part of the alternating anode current of said power stage flowing through it.

3. A transmitter as defined in claim 1, characterized by the feature that said source of audio frequency modulating potential includes a power amplifier stage and that last said means includes at least one choke coil connected in circuit with said audio frequency power amplifier stage from which is taken at least part of the alternating anode potential of said high frequency amplifier stage to modulate the anode potential thereof.

4. A transmitter as defined in claim 1, characterized by the feature that the anode voltages of the amplifier and power stages respectively of said high frequency part are equal.

5. A transmitter as defined in claim 1, characterized by the feature that said last means includes a transformer connected in the anode circuit of the power stage of said high frequency part.

6. A transmitter as defined in claim 1, characterized by the feature that said last means includes a transformer connected in the cathode circuit of the power stage of said high frequency part.

7. A transmitter as defined in claim 1, charac-

terized by the feature that said last means includes a transformer connected in the anode circuit of the power stage of said high frequency part, the end stage of the low frequency part acting on the primary winding of said transformer, the alternating anode current of the power stage of said high frequency part flowing between an end point in the secondary winding of said transformer, said end point being located between said winding point and the anode of said high frequency power stage, the potential at the other end point of said secondary winding being supplied to the grid of said high frequency power stage.

8. A transmitter as defined in claim 1, characterized by the feature that said last means includes a transformer connected in the anode circuit of the power stage of said high frequency part, the end stage of the low frequency part acting on the primary winding of said transformer, the alternating anode current of the power stage of said high frequency part flowing between an end point in the secondary winding of said transformer, said end point being located between said winding point and the anode of said high frequency power stage, the potential at the other end point of said secondary winding being supplied to the grid of said high frequency power stage, and a choke coil connected in parallel to that part of the transformer secondary winding through which the alternating anode current of the high frequency power stage flows, said choke coil supplying the potential required for modulating the anode potential of said high frequency amplifier stage.

9. A transmitter as defined in claim 1, characterized by the feature that said last means in-

cludes a transformer connected in the cathode circuit of the power stage of said high frequency part, at least part of the primary winding of said transformer having alternating anode current of the high frequency power stage flowing through it, and the potential for modulating the anode potential of the high frequency amplifier stage is taken from the secondary of said transformer.

10. A transmitter as defined in claim 1, characterized by the feature that said last means includes a transformer connected in the cathode circuit of the power stage of said high frequency part, a part of the primary winding of said transformer having alternating anode current of the high frequency power stage flowing through it, and the potential across the remaining part of the primary winding being supplied to the control grid of the high frequency power stage.

11. A transmitter as defined in claim 1, and further including phase adjusting means for adjusting the phase of at least one of the modulating potentials to which said grid and anode are simultaneously subjected.
